(57) **CLAIM**

The ornamental design for a page turning device, as shown and described.

DESCRIPTION

FIG. 1 is a front, right and top perspective view of a page turning device, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion of FIG. 1 thereof. The dash-dash broken lines shown in the drawings illustrate portions of the page turning device that form no part of the claimed design.

The broken lines depict the boundary of the enlarged view of the page turning device and form no part of the claimed design.
